UNITED STATES PATENT OFFICE.

JOHN W. SHEPERDSON, OF HARRISBURG, PENNSYLVANIA.

ROLLING-MILL GUIDE.

1,110,463.

Specification of Letters Patent. Patented Sept. 15, 1914.

Original application filed November 13, 1912, Serial No. 731,077. Divided and this application filed May 16, 1914. Serial No. 838,998.

To all whom it may concern:

Be it known that I, JOHN W. SHEPERDSON, a subject of the King of Great Britain, residing at Harrisburg, in the county of Dauphin and State of Pennsylvania, have invented certain new and useful Improvements in Rolling-Mill Guides; and I do hereby declare the following to be a full, clear, and exact description of the invention, 10 such as will enable others skilled in the art to which it appertains to make and use the same.

My invention relates to rolling mill apparatus with special references to the guide equipment thereof and is applicable to metal rolling mills known as two-high and three-high mills, and is particularly adapted for use in connection with those of the continuous type, and is a division from my co-pending application filed November 13th, 1912, Serial No. 731,077.

Although my invention is adapted for use in connection with blooming mills, billet mills, bar mills and rod mills, I will, for the sake of simplicity of description, refer to the rolled piece in all cases as a bar.

One of the objects of my invention is to provide a construction and arrangement of the entry guides which receive and direct 30 the rolled bar to the passes of the rolls.

In order that the rolling operation may not be interrupted, I may provide in each set of rolls a plurality of passes of the same contour, whereby the rolling operation of 35 any size and section may be shifted from one pass to another, in case where the first pass becomes worn or otherwise inoperative for the purpose intended. I may also provide passes of different forms in the same 40 pair of rolls adapted to operate upon and produce different sizes and sections, if desired.

My invention provides apparatus which has, by reason of its distinctive construction, 45 such a reduced lateral displacement that a simultaneous guide equipment is provided for adjoining roll passes, whereby the guide of one pass will not interfere with the guide of the adjacent pass.

In order to more fully describe my invention, I will now refer to the accompanying one sheet of drawings on which like numerals indicate like parts.

Figure 1 is a top plan view of an entering guide adapted to coöperate with the rolls.

Fig. 2 is a vertical longitudinal elevation of the entering guide taken on the line II—II of Fig. 1.

The rolls are indicated as 1 and 2, while 3 represents the entering guides which are supported at one end on the guide rest mounted on the housings as shown, while the other end 4 of said entrance guide is supported on the pedestal 5, which latter is provided with a suitable base secured to a solid foundation (not shown). The entering guide is provided with side guides 6 formed integral therewith and preferably tapering from their inner ends, to their outer ends as shown, thereby providing 60 guiding passages to the roll passes. The outer part 4 of the base of the entering guide is sloping as shown, thereby forming an inclined surface to better receive and direct a bar to the roll pass in connection with 65 the tapering side guides 6, 7, 8 and the sloping cover 9, thus forming an adjustable funnel-shaped construction adapted to guide bars of different sizes and forms. The entering guide plate is secured in position by 70 the bolts 10 which pass through slotted holes 11 provided therein and is locked in position by the keys 12 which pass through slots in the ends of the bolts 10 as shown. Only 75 one of each pair of bolts 10 may be used 80 and its head may be seated in either of the slots in the pedestal 5, or in either of the slotted holes 11 in each of the entering side guides 6, thereby providing different positions of the entering guide, as desired. Fur- 85 ther smaller adjustments of the same can be made by reason of the slotted holes 11 pro- 90 vided for this purpose. This arrangement permits lateral and longitudinal adjustment 95 of the entering guides to adapt them to co- 95 operate with the rolls as desired. The inner ends of the entering side guides 6 are pro- 100 vided with intermediate swinging side guides 7 and the outer swinging side guides 8. These swinging guides adjoin the rolls and are adapted to be moved laterally and secured in position to accommodate and 105 guide bars of different widths. These adjustable side guides 7 and 8 are hinged and pivoted to the fixed side guides 6 by the pivot pins 13 as shown, which pass through the hinge lugs 14, 15 and 16 formed thereon, as shown clearly in Figs. 1 and 2. The inner end of the entrance guide is supported 110 on a guide rest by means of its projecting

lugs 17 which contact therewith, as shown in Fig. 2. The upper edges of the inner ends of the adjustable entrance guides 7 and 8 are elevated and tapering as shown and each pair is provided with a cover 9, which rests on the aforesaid upper edges of the adjustable swinging guides to hold them firmly in the position desired, thereby forming a closure and completing the tapered 10 guide opening.

Short bars or blocks 18 rest on top of the tapered ribs or flanges of each of the covers 9 and hold them and the swinging guides firmly in place by the action of the keys or 15 wedges 19 which are driven between the bars 18 and the longer bar 20, which latter is secured at each end to the roll housing, thereby serving as an abutment against which the wedges 19 operate.

20 Although I have shown and described my improvements in considerable detail, I do not wish to be limited to the exact and specific details shown and described, but may use such substitutions, modifications or 25 equivalents thereof, as are embraced within the scope of my invention, as pointed out in the claims.

Having thus described my invention, what I claim and desire to secure by Letters 30 Patent is:—

1. An entering guide for rolling mills comprising a base the outer end of which is inclined and provided with a plurality of tapered side guides upwardly projecting 35 therefrom, swinging side guides pivoted to the inner ends of the side guides aforesaid, and means for adjustably securing the same in position.

2. An entering guide for rolling mills 40 comprising a base provided with a plurality of side guides projecting upwardly therefrom, swinging side guides pivoted to the inner ends of the side guides aforesaid, a cover mounted on the inner ends of each of

the pairs of swinging guides, and means 45 for adjustably securing the same in position.

3. An entering guide for rolling mills comprising in combination with the rolls, a base, the outer portion of which inclines 50 upwardly toward the rolls, a plurality of tapered side guides formed integral with, and projecting above, said inclined base, a plurality of swinging side guides pivoted to the inner ends of the side guides aforesaid, 55 the upper edges of said swinging side guides being downwardly inclined toward the rolls, covers mounted on said inclined upper edges, and means for adjustably securing the same in position.

4. An entering guide for rolling mills comprising in combination with the rolls, a base, the inner portions of which are adapted to register with, and are contiguous to, the lower surfaces of the roll passes, the 60 outer portion of said base being inclined downwardly in a direction away from the rolls, a plurality of tapered side guides formed integral with, and projecting upwardly from, the outer portion of said base, 70 the thicker ends of said side guides being nearer the rolls, a plurality of swinging side guides pivoted to the thicker inner ends of the tapered side guides aforesaid, the inner 75 portions of the upper edges of said swinging guides being downwardly inclined toward the rolls, covers mounted on said inclined upper edges and means for adjustably securing same in position, the whole forming a plurality of adjustable openings tapering in both directions toward the roll passes. 80

In testimony whereof I hereto affix my signature in the presence of two witnesses.

JOHN W. SHEPERDSON.
